F. SATTERSTROM

UNIVERSAL CONTACT BAR FOR ELECTRIC CIRCUITS

Filed Oct. 29, 1920

FIG. 1.

FIG. 2

FIG. 3

INVENTOR
FERNAND SATTERTHWAITE

BY Paul & Paul
ATTORNEYS

UNITED STATES PATENT OFFICE.

FERDINAND SATTERSTROM, OF HASTINGS, MINNESOTA, ASSIGNOR TO MAGNETIC POWER TRANSMITTER COMPANY, OF FARIBAULT, MINNESOTA, A CORPORATION OF MINNESOTA.

UNIVERSAL CONTACT BAR FOR ELECTRIC CIRCUITS.

Application filed October 29, 1920. Serial No. 420,484.

To all whom it may concern:

Be it known that I, FERDINAND SATTERSTROM, a citizen of the United States, resident of Hastings, in the county of Dakota and State of Minnesota, have invented certain new and useful Improvements in Universal Contact Bars for Electric Circuits, of which the following is a specification.

This invention relates to improvements in contact means designed particularly for use in connection with a series of electric circuits such as are provided with electrically actuated typewriters, though capable of being used wherever a plurality of electrically controlled devices are arranged to be actuated from a single battery or source of electric power or energy.

The present application is in part generic to and in part a continuation of my Patent No. 1,395,599, issued November 1, 1921, for electrical actuating means for typewriter type bars and other devices.

It is well understood that when an electric current is broken a spark occurs which 25 corrodes, burns or otherwise ruins any contact excepting one made of platinum, thereby making such contact unreliable. Platinum has been found to be the only metal which will withstand, for a long period of 30 time, the effect produced by the breaking of an electric current.

In devices where many make and break contacts are to be used, as in a typewriter, the number of contacts varying from possibly 40 to 80, as may be the case, the work and expense of supplying a separate pair of platinum contact points for each key is necessarily expensive.

One of the objects of this invention is to 40 make use of only a single pair of contact points for operating levers, such as type keys, whatever their number may be, acting with a universal contact forming bar located in proper relation to the other elements of the device.

The invention consists generally in a universal contact bar or connector arranged in operative relation to a contact point or pair of contact points, and a series of operating 50 keys or levers, whereby an electric circuit may be closed through said pair of contact points upon the operation of any one of said keys or levers.

In the accompanying drawings forming part of this specification,

Figure 1 is a plan view of a portion of a typewriter key-board, with my invention applied thereto.

Figure 2 is a vertical section of the key-board showing one arrangement of the universal contact bar or connector and showing also the connection of the circuits to the magnets of an electrically actuated typewriter.

Figure 3 is a detail illustrating the operation of the universal contact bar, or connector.

In the drawings, 2 represents a portion of the frame of a typewriter machine, which furnishes support for a series of type bars 3, each of which is provided with a suitable type 4. The frame 2 is preferably provided with a plate 5 supporting lugs 6 to which the type-bars 3 are pivoted. The type-bars are arranged to be operated by actuating levers 8, each pivoted to a bracket 9 on the frame of the machine and connected to the type-bar by a link 10. A connecting member 12 is pivoted to each of the actuating levers 8 and the position of these members is controlled by the armature 21 of the selecting magnet 20. An actuating or power magnet 30 is provided with an armature 29 arranged to actuate a universal power bar 24.

These parts are arranged substantially as set forth in my said pending application whereby, when the magnets are energized, the type-bars will be actuated to impress the type upon paper suitably placed in the machine, substantially as described in my said pending application.

I provide a selecting magnet 20 for each of the type-bars and a key-board is employed having a key, or a key-lever 40, for each selecting magnet. A suitable arrangement of key-board with the key-levers 40, each provided with a suitable key-top 41, is illustrated in Figures 1 and 2 of the drawings. As here shown the key-board is provided with a suitable frame 38 upon which the key-levers are pivoted by suitable pivotal supports 39. These keys are arranged in any preferred manner.

Arranged beneath the key-levers, and extending transversely thereof is a rock shaft

42 mounted in suitable bearings 43, 43. Secured to this rock shaft preferably near its end are crank arms 44 supporting or formed integrally with the universal contact bar or connector 45. The crank arms preferably extend to the rear of the rock shaft 42 and springs 46 are connected to said crank arms and to stationary points on the machine frame. Suitable stops 44' are preferably provided to limit the upward movement of the bar 45. The springs 46 tend, at all times, to hold the universal contact bar at the upper limit of its movement, while permitting said bar to be moved downward 15 when pressure is applied thereto at any point in its length.

Arranged beneath each of the key-levers is a contact arm or member 50 preferably pivoted to a suitable insulated stationary support 51 on the frame of the key-board and arranged to be held in an elevated position by a suitable spring 52. An insulating block 53 is preferably secured to the under side of each key-lever 40, and the contact arms 50 are normally held with their upper or forward ends resting against the under side of said insulating block.

Beneath the contact bar 45 is arranged a contact spring or member 54 having preferably a platinum contact point 54'. The spring 54 is secured upon a suitable insulating support and is preferably electrically connected to a circuit wire B extending to the power magnet 30, said power magnet 35 having ground connections at B'.

A suitable plate of insulating material 55 is preferably arranged upon the frame of the key-board. On this plate the supports 51 for the contact arms 50, the bearings 43 for the rock shaft 42, supporting the universal contact bar 45, and the contact spring or member 54, are all supported.

Each of the contact arms 50 is in electrical connection, through a circuit wire C, 45 with the corresponding selecting magnet 20, and each selecting magnet has a ground connection C'. Supported upon the insulating plate 55 beneath the contact spring or member 54 is a second contact spring or member 56 also provided with a platinum contact point 56' adapted to make contact with the platinum 54' on the spring 54, when said last named spring is depressed by the universal contact bar.

The spring 56 is connected to an electric circuit wire D which is grounded at D', and is connected to a suitable battery E.

It will be seen that with this arrangement of the universal contact bar or connector 60 and the co-operating elements provided in the key-board, any number of circuits may be closed with a single pair of contact springs, and, therefore, it is only necessary to provide a single pair of contact points 65 for any number of circuits.

I have shown in the drawings an air gap between the universal contact bar or connector 45 and each of the contact arms 50, and also an air gap between the bar 45 and the upper contact springs 54, and I 70 prefer this construction, but these air gaps are not necessary to the operation of the device. The upper surface of the bar 45 may be normally in contact with the under surface of all of the contact arms 50, and its under surface normally in contact with the spring 54. In this case the only air gap is between the contact points 54' and 56'. When any one of the key-levers is depressed the corresponding arm 50 forces the bar 45 80 downward forming an air gap between the bar 45 and all of the other arms 50, and pressing the two contact points 54' and 56' of the springs 54 and 56 into electrical contact with each other. 85

The operation of the entire mechanism will be more fully seen by reference to my said former Patent No. 1,395,599.

If preferred the upper spring 54 may be omitted and the contact point 54' may be 90 arranged directly on the under surface of the bar 45 as shown in Figures 4, 5 and 6 of my said Patent No. 1,395,599. These modifications will not change the operation of the device. 95

I claim as my invention:

1. The combination, with a suitable circuit closing contact spring, of a movable contact bar or connector arranged to contact therewith, a series of independent circuit 100 closing arms, and means for bringing any one of said arms into contact with said bar or connector to move the same into engagement with said contact spring for the purpose of closing an electric circuit, 105 through the selected and operated arm.

2. A universal contact bar or connector, in combination with a circuit closing member, and a series of operating arms, each arranged to engage said bar, and move the 110 same into position to close an electric circuit through said contact member and the operated arm.

3. A universal contact bar or connector in combination with a circuit closing member, and a series of operating arms or members by which said universal bar may be moved to engage said contact member and close a circuit through said contact members, the universal bar and the operated 115 arm.

4. The combination, with a plurality of electric circuits, and a source of electrical energy for all of said circuits, of a universal electric connector and a plurality of bars 120 each movable into contact with the connector and movable with the connector to connect any selected circuit with said source of electric energy.

5. The combination, with a plurality of 130

- electric circuits, and a source of electrical energy common to all of said circuits, and provided with a single contact device, of a universal circuit connector means movable to be first connected to said connector, and thereafter by further movement to be brought into electrical connection with said contact devices. 5
6. The combination, with a plurality of electric circuit conductors, a source of electric energy, and a contact device connected therewith, of a universal contact bar, means for first establishing an electric contact between any selected circuit conductor, and 10 said contact bar, and thereafter establishing an electrical contact between said bar and said contact device. 15
7. The combination, with a plurality of electric circuit conductors, a battery, an electric contact device connected with said battery, of a universal contact bar or connector, an actuating lever for each circuit conductor, having an electrical connection with said conductor, and arranged to first 20 engage said contact bar and thereafter to move said bar into electrical connection with said contact device. 25
8. The combination, with a plurality of electric circuit conductors, a source of electric energy, and an electric contact device connected therewith, of a universal electric 30
- connector, and means connected with each of said circuit conductors and arranged to engage and move said universal connector and to establish an electric connection between said connector and said contact device, whereby a circuit may be closed through any one of said circuit conductors. 35
9. The combination, with a plurality of electric circuit conductors, a source of electric energy, and an electric contact device connected therewith, of a universal electric connector, and means connected with each of said circuit conductors for establishing contact with said universal connector and thereafter producing contact between said universal connector and said contact device. 40 45
10. The combination with a plurality of circuit closing contact springs having an electric contact between the springs, a movable contact bar or connector arranged to contact with one of said springs to close the contact between the springs, a series of independent circuit closing arms, and means for bringing any one of said arms into contact with said bar, or connector to move the same into engagement with one of said springs to close the electric circuit through the selected arm. 50 55

In witness whereof, I have hereunto set my hand this 15th day of October 1920. 60

FERDINAND SATTERSTROM.
